UNITED STATES PATENT OFFICE.

HOLLIE N. OAKLEY, OF TERRE HAUTE, INDIANA.

REFRIGERATING APPARATUS.

Application filed March 21, 1919. Serial No. 284,135.

To all whom it may concern:

Be it known that I, HOLLIE N. OAKLEY, a citizen of the United States, residing at Terre Haute, in the county of Vigo and State of Indiana, have invented certain new and useful Improvements in Refrigerating Apparatus, of which the following is a specification.

My said invention relates to refrigeration and more particularly to refrigerating rooms for keeping meats, etc., in storage, wherein a portable receptacle containing ice is used for lowering the temperature of the air in the room or compartment in which such perishable articles are stored. Another object is to provide means carried with the portable ice receptacle for circulating the chilled air.

With these and other objects in view, the invention consists in the combination and arrangement of parts, as more fully described in the following specification and particularly pointed out in the appended claim, reference being had to the accompanying drawings forming a part hereof, on which like reference characters designate similar parts in the views, of which:

Figure 1 is a vertical sectional view showing the interior of a refrigerating room provided with a refrigerating apparatus constructed and arranged in accordance with my said invention.

Figure 2 a perspective view showing the exterior of the ice container and refrigerating apparatus, and

Figure 3 a detail vertical sectional view showing a somewhat modified construction.

In said drawings the portions marked "A" represent the refrigerating room; "B" the ice container and "C" the fan for inducing air circulation.

The room "A" may be any room appropriate for the purpose, but preferably constructed as a refrigerating room provided with a door 10 for entrance, to arrange articles to be preserved therein, and with a door 11 through which the ice may be deposited into the ice container "B."

The room is, of course, fitted with devices for hanging, or otherwise containing, the articles to be preserved, which may be of any appropriate construction and arrangement and are not shown.

The ice container "B" is preferably of portable construction, so that it may be

moved from position to position within the room in order to have it located where the best results can be obtained in view of the arrangement, or distribution of the articles in the room. It is formed of appropriate walls and has a grate 12 mounted on appropriate supports 13 in its lower end on which the ice is supported. Below the ice it is provided with an opening 14 in one wall over which the casing containing the fan "C" 65 is mounted.

Said fan "C" is of any appropriate construction comprising an electric motor connected with a source of power by wires 18 as will be readily understood.

A drip pipe 15 leads from the bottom of the ice container into a waste pipe 16 leading through the floor of the room. Said drip pipe 15 should be a flexible hose so as not to interfere with the movement of the container "B" from position to the position within the room.

In Figure 1 I have shown the top of the container "B" open and slightly below the ceiling of the room "A," while in Figure 3 80 the top extends to said ceiling and air inlet openings 17 are formed through the walls near the top. In this figure the ice container is shown resting upon the floor of the refrigerating room and is intended to remain 85 stationary.

Other modifications in the construction and arrangement will readily suggest themselves.

In operation the room "A" is filled with 90 meat, or other things to be preserved, the ice container "B" is filled with ice and the doors are closed. The electric current is then turned on to drive the fan "C," which operates to draw the cold air through inlets 95 at the top of the ice chamber and expel it through the opening 20 in the fan casing into the room and near the bottom thereof, driving said cold air across the bottom of the room to the opposite side, and at the 100 same time inducing a draft of air into the upper end of the ice chamber, either through its open top, or through appropriate openings in the sides near the top, thus keeping the air in constant circulation around the 105 ice contained in the chamber and the room containing the perishable things, thereby maintaining a low temperature in said room in a very efficient, convenient and inexpensive manner.

Having thus fully described my said invention, what I claim as new, and desire to secure by Letters Patent, is:

A refrigerating apparatus comprising an enclosed room for the storage of meats, etc. and formed with an ice-receiving opening in the ceiling, a door by which said opening is normally closed and also formed with another opening provided with a door to afford access to said room, and a portable ice container mounted to be moved about said room and formed with an open top spaced from the ceiling of the room and adapted when in position to register with the ice-receiving opening in said room ceiling and with air outlets in the lower portion thereof, and

having a casing mounted on one side for housing a fan, a power connection leading to said fan for operating the same, and a flexible pipe connected with the bottom of the ice container leading to a drain to afford means for conducting away the drip from the room regardless of the position of the ice container, substantially as set forth.

In witness whereof, I have hereunto set my hand and seal at Terre Haute, Indiana, this 19th day of March, A. D. nineteen hundred and nineteen.

HOLLIE N. OAKLEY. [L.S.]
